METHOD OF AND MEANS FOR SEVERING
AND FEEDING A WEB OF FLEXIBLE MA-
TERIAL

Joseph Peyser, Mount Vernon, N. Y.

Application March 28, 1935, Serial No. 13,473

8 Claims. (Cl. 164—17)

This invention relates to a method of and means for severing and feeding a web of flexible material, and has for its main object and feature the accurate and speedy production of covers for match-books from a web and the feeding of such covers to the conveyer of a match-book machine of the type shown for instance in my application Ser. No. 11,269 filed March 15, 1935.

In the accompanying drawings the invention is shown in a concrete and preferred form in which:

Fig. 1 is a top plan view of a device embodying the invention;

Fig. 2 is a view partly in side elevation and partly in section of the device shown in Fig. 1;

Fig. 3 is a perspective fragmentary view of the feed-table, deflecting member and knife;

Fig. 4 is a transverse vertical sectional view substantially on the plane of line 4—4 of Fig. 2;

Fig. 5 is a more or less diagrammatic perspective view of the feeding and severing elements of the device.

10 indicates a feed-table, the outer end of which is provided with a cutting edge 11, and 12 is a recess in the side of the table, the purpose of which will appear later. Below said feed-table and forwardly thereof is a support 13 to receive a sheet or section from table 10. 14 indicates a knife to cooperate with edge 11 to sever a section from a web fed along table 10, and 15 is a deflecting member to deflect a portion of the web into recess 12. Knife 14 and deflecting member 15 are mounted on a slide 16 reciprocating in guides 17, and slide 16 is actuated from rockshaft 18 by means of connections 19.

20 indicates a cover conveyer, the upper run of which is on a level with support 13. Said conveyer is here advanced intermittently step by step by suitable means (not shown), and it will be noted that support 13 is cut away at 21 to permit feed dogs 22 to pass up through said support to engage the back edge of the sheet and carry it along. 23 are reciprocating mem-

bers sliding in the framework, and provided with projections 24 to feed a sheet from support 13 onto conveyer 20. 25 indicates a rockshaft actuating the members 23 by means of connection 26, and actuating the rockshaft 18 by means of connections 27. Rockshaft 25 is actuated from eccentric 28 by means of connections 29, and eccentric 28 is mounted on shaft 30 carrying gear 31 receiving its motion from gear 32 on shaft 33. 34 indicates a pair of feed rollers here driven continuously to feed web W forward from a web

roll (not shown) to provide a slack and pendent portion W¹ in the web. 35 and 36 indicate a pair of intermittently acting feed rollers to alternately feed and release the web, and it will be noted that one of said rollers, here 36, is mutilated or has high and low spots as shown, the web being fed forward when high spot of 36 engages 35, and being released when the low spot of 36 comes opposite 35. Any suitable means are employed to continuously drive rollers 34, 35 and 36, such, for instance, as sprocket chain 37 passing over sprockets 38, 39, 40 and 41.

Web W is severed partially at W² before it is fed through rollers 35 and 36, and this may obviously be done while the web is in transit from its roll, or it may be done by a separate operation and the web rewound into roll form. This partial severance W² is transversely of the web at one of its side edges and is at predetermined points in the length of the web, partial severance or slit W² defining the size of the cover or sheet to be completely severed from the web. Said web is threaded through rollers 34, 35 and 36 with a slack portion at W¹, as indicated in Fig. 2, and the forward end of the web placed on feed-table 10. Rollers 34 maintain slack and pendent portion W¹ in the web, and rollers 35 and 36 draw intermittently from said slack portion and advance the web along feed-table 10. The high and low spots on roller 36 are of such length and the speed of rotation of rollers 35 and 36 are so calculated and timed that with each intermittent feeding movement of said rollers an amount of web in excess of the length defined by the distance between slits W² is advanced. In so advancing the web, the partially severed portion of the web passes over recess 12 and, when the rear end of the forward web section is above said recess, deflecting member 15, the face of which is in line with that of knife 14, descends deflecting said partially severed portion into recess 12 thereby blocking the web when the undeflected portion of the next succeeding web section encounters the face of the deflecting member. Rollers 35 and 36, however, continue momentarily to feed the remainder of the web whereby a buckle W³ is formed in said remainder of the web. At substantially the same time that the undeflected portion of the next succeeding web section encounters the face of the deflecting member, the partial line of severance reaches the plane of the cutting edge of knife 14 and the latter almost immediately completely severs the web in line with the partial severance, and this action also tends to block the web and

to create the buckle aforesaid as rollers 35 and 36 still continue to urge the remainder of the web forward. Rollers 35 and 36 now release the web and the weight of slack W¹ retracts the web 5 a certain distance and buckle W³ disappears. The object of the slight overfeed caused by rollers 35 and 36 is to render certain that sufficient web is always fed so that a cover of proper size will be severed from the web, deflecting member 15 and knife 14 preventing too large a cover from being severed from the web. In order to prevent buckle W³ from being formed 10 too closely adjacent to the cutting devices, cover plates 42 may be arranged above table 10 in closely spaced relation thereto and, if desired, 15 spring-pressed plungers 43 or light springs may be carried by slide 16 to bear upon the paper and prevent slack W¹ from retracting the web too far. The deflected portion W⁴ regains its 20 shape and is not permanently deformed out of the plane of the web or sheet, and to assist the severed sheet W⁵ in passing to support 13, ejectors 44 carried by slide 16 may be used. Members 23 now advance and sheet W⁵ is transferred to conveyer 20 of the match-book machine.

I claim:

1. The method of severing a web of flexible material into predetermined lengths which consists in: partially severing the web transversely at a predetermined point in its length; advancing said web an amount in excess of that defined by its partial severance; deflecting the partially severed portion of the advancing web and completely severing it in line with its partial severance thereby causing a buckle to be formed in the remaining and advancing portion of the web; and retracting the buckled portion of the web.
- 40 2. The method of severing a web of flexible material into predetermined lengths which consists in: partially severing the web transversely at predetermined points in its length; intermittently advancing said web an amount in excess of that defined by its partial severance; deflecting the partially severed portion of the front section of the advancing web and completely severing it in line with its partial severance thereby causing a buckle to be formed in 45 the remaining and advancing portions of the web; and, intermittently and alternately with the advance and complete severance of the web, retracting the buckled portion of the remainder of the web.
- 55 3. The method of severing a web of flexible material into predetermined lengths which consists in: partially severing the web transversely at a predetermined point in its length; maintaining a slack and pendent source of supply of said partially severed web; advancing said web from said slack supply an amount in excess of that defined by its partial severance; deflecting the partially severed portion of the advancing web and completely severing it in line with its partial severance thereby causing a buckle to be formed in the remaining and advancing portion of the web and stopping the advance 60 of said remaining web portion thereby allowing the weight of said slack and pendent source of supply to partially retract the buckled portion of the web.

4. The method of severing a web of flexible material into predetermined lengths which consists in: partially severing the web transversely at predetermined points in its length; maintaining a slack and pendent source of supply of said 5 partially severed web; intermittently advancing said web from said slack supply an amount in excess of that defined by its partial severance; deflecting the partially severed portion of the front section of the advancing web and completely severing it in line with its partial severance thereby causing a buckle to be formed in the remaining and advancing portion of the web; and, intermittently and alternately with the advance and complete severance of the web, 10 allowing the weight of said slack and pendent source of supply to partially retract the buckled portion of the web.

5. A web severing and feeding device including: a feed-table having a cutting edge at its outer end and a recess at its side; means to feed a web partially severed at predetermined points, along said table, the partially severed portion of the web passing over the recess aforesaid; a deflecting member to deflect the partially severed portion into the recess aforesaid while the web is moving; and a movable knife to complete the severance of said web in line with its partial severance.

6. A web severing and feeding device including: a feed-table having a cutting edge at its outer end and a recess at its side; intermittently acting means to alternately overfeed and release a web, partially severed at predetermined points, 35 along said table, the partially severed portion of the web passing over the recess aforesaid; means to maintain a slack and pendent supply of said web for the use of the intermittently acting means; a deflecting member to deflect the partially severed portion into the recess aforesaid 40 while the web is moving; and a movable knife to complete the severance of said web in line with its partial severance.

7. The method of severing a web of flexible material into predetermined lengths which consists in: partially severing the web transversely at one of its side edges at predetermined points in its length; advancing said web an amount in excess of that defined by the distance 45 between successive lines of partial severance; deflecting the partially severed portion of the advancing web before completely severing it and completely severing said advancing web in line with its partial severance, thereby causing a 50 buckle to be formed in the remaining and still advancing portion of the web; and retracting the buckled portion of the web.

8. A web severing and feeding device including: a feed-table having a cutting edge at its outer end and a recess at its side; means to feed a web partially severed at predetermined points, along said table, the partially severed portion of the web passing over the recess aforesaid; a movable knife to complete the severance 60 of said web in line with its partial severance; and a deflecting member to deflect the partially severed portion of the web into the recess aforesaid while said web is moving and before the line of partial severance reaches the knife.

JOSEPH PEYSER.
